(57) **CLAIM**

The ornamental design for a surgical needle holder with tip guard, as shown and described.

DESCRIPTION

FIG. 1 is a front elevational view of a surgical needle holder with tip guard, showing my new design;

FIG. 2 is a side elevational view thereof;

FIG. 3 is a side elevational view thereof, opposite that shown in FIG. 2;

FIG. 4 is a front elevational view thereof, with the jaws shown in open position;

FIG. 5 is an enlarged fragmentary cross-sectional view thereof, taken along the lines 5—5 of FIG. 4; and,

FIG. 6 is an enlarged perspective view thereof.

The broken line showing in FIGS. 2, 3, and 6 are for illustrative purposes only and forms no part of the claimed design.

The surfaces or portions of the article not shown in the drawing or described in the specification forms no part of the claimed design.
